UNITED STATES PATENT OFFICE.

KUMAJIRO OKUBO, OF DENVER, COLORADO.

CLOTHES BRUSH AND HANGER.

1,108,848.

Specification of Letters Patent.

Patented Aug. 25, 1914.

Application filed September 16, 1913. Serial No. 790,101.

To all whom it may concern:

Be it known that I, KUMAJIRO OKUBO, subject of the Emperor of Japan, residing at Denver, in the city and county of Denver and State of Colorado, have invented certain new and useful Improvements in Clothes Brushes and Hangers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in combined clothes brushes and hangers and has for one of its objects to provide a device of this nature which, when not in use as a clothes hanger may be "knocked down" and thereby caused to occupy only a comparatively small space, making my invention of particular utility to travelers.

Another object of the invention is to provide extensions which are slidable upon the extremities of the clothes hanger making it adjustable to garments of all sizes.

Still another object is to provide auxiliary arms extending outwardly upon one side of the main arms, which arrangement I have found to be particularly useful for ladies' garments of light material, especially silk and lace.

A further object of the invention is to so arrange the hanger when in its "knocked down" condition as to constitute a handle for the brush.

Other objects will appear hereinafter as I proceed with the description of that embodiment of my invention which for the purposes of the present application I have illustrated in the accompanying drawing in which:

Figure 1 is a side elevation of my improved device. Fig. 2 is a top plan view of the device showing the extensions in one position in full lines and in another position in dotted lines. Fig. 3 is a plan view of the brush and the fixed arm of the hanger. Fig. 4 is a side view of the brush and hanger in "knocked down" position. Fig. 5 is an under face view of the removable hanger arm. Fig. 6 is a detail of one of the extensions. Fig. 7 is a detail of the suspending hook. Fig. 8 is a cross section taken upon the line 8-8 (Fig. 4).

Similar reference characters refer to like parts in all the views.

In the drawing 5 represents a clothes brush of ordinary form and construction having roll edges 6. (See Fig. 8.) Upon one side of the brush back is fastened by means of screws 7 a longitudinally extending arm 8 formed preferably of metal, the sides of which near the outer extremities are turned under at 9 to form guide grooves for a purpose that will appear hereinafter. A second arm 10 of similar shape is adapted to be removably mounted upon the opposite end of the brush by means of turned flanges 11 which, when the arm is pushed toward the middle of the brush clamp upon the roll edges 6 thereof. The outer extremity of the arm 10 is also provided with guide grooves 9 identical in shape with those upon the arm 8.

Near the inner end of the arm 10 is a perforation 12, which registers with a hole 13 in the brush back when the arm is in the position illustrated in Figs. 1 and 2. A suspending hook or ring 14 has a straight portion 15, which may be set into the registering holes 12 and 13, and an angularly projecting part 16 which is adapted to be sprung into the opening of a screw-eye 17, which extends through the arm 8 into the brush back.

The hook 14, is made of spring material and so formed that the ends 15 and 16 tend to take positions further separated than those they must occupy when the hook is in place upon the brush, thus maintaining the projecting part 16 in place in the screw eye.

Parts 18 which I shall hereinafter refer to as extensions are formed of spring wire bent into substantially U-shaped form with the extremities flared away from each other as illustrated in Fig. 6. When the device is in use as an ordinary coat-hanger these extensions are slid into the guide grooves 9 of the arms 8 and 10, and may be adjusted lengthwise to any desired position, the outwardly exerted spring pressure of the extremities of the extensions holding the latter securely in place in any desired position.

In one side of the brush back I bore holes 19, which are adapted to receive the extremities of the extensions 18. When the extensions are thus arranged, a support of substantially semi-circular form is provided, which as heretofore stated is particularly useful for garments of light material which

it is desired to maintain in a smooth condition in order to prevent wrinkling.

My improved device may be put into very small compass by removing the hook 14, 5 withdrawing the arm 10, from the end of the brush and sliding it upon the opposite end of the brush above the arm 8, a recess 20, being provided in the arm 10, to extend about the screw eye 17, when the arm is in 10 this latter position. The extensions 18, will then be pushed inwardly as far as they will go. If desired, the hook 14, may also be clamped about the brush back. It will be apparent that in this arrangement of the 15 hanger parts, they form a handle for the brush 5, as shown in Fig. 4.

From the foregoing description it is believed that the operation of my improved brush and garment hanger will be apparent 20 without further explanation.

I claim as my invention:

1. A clothes hanger comprising a central member, a suspending means attached to said central member; two diametrically opposed 25 arms extending in a substantially horizontal direction from said central member and two other arms removably mounted upon the central member and extending horizontally therefrom upon one side of the first mentioned arms, the second named arms being 30 so arranged as to form equal angles between each pair of adjacent arms.

2. A clothes hanger comprising a central member, two horizontally arranged arms 35 extending outwardly from said central member in diametrically opposed directions, removable extensions slidably mounted upon the extremities of said arms, and means for removably mounting said extensions upon 40 said central member.

3. In combination, a central member, suspending means removably attached to the back of said member, an arm extending

longitudinally from one end of the back of said member to which it is fixed, and a second arm removably mounted upon the back of said member to extend in a direction diametrically opposed to that of the first arm, said second named arm being also adapted to be removably mounted upon the 50 central member above said fixed arm.

4. In combination, a central member, means for suspending the same, and arms extending longitudinally from either end of said member to constitute a clothes hanger, 55 at least one of said arms being removable, and adapted to be removably mounted upon the central member above the other arm, for the purpose set forth.

5. In combination, a central member, arms 60 extending longitudinally from either end of said member to constitute a clothes hanger. the central member and one of said arms having registering perforations, and means for suspending the hanger, one extremity of 65 which enters said perforations for securing the last named arm in place.

6. In combination, a central member, arms extending longitudinally from either end of said member to constitute a clothes 70 hanger, the central member and one of said arms having registering perforations, means mounted upon said central member and having a perforated head projecting above the same, and a second means for suspending 75 the hanger, one extremity of which enters said registering perforations while the other extremity is adapted to be sprung into the perforated head of the first named means.

In testimony whereof I affix my signature 80 in presence of two witnesses.

KUMAJIRO OKUBO.
